CABINET DOOR

Warren A. Dillen, Louisville, Ky., assignor to
H. J. Scheirich Company

Filed Sept. 6, 1972, Ser. No. 286,665

Term of patent 14 years

Int. Cl. D6—06

U.S. Cl. D6—192

FIG. 1

FIG. 2

FIG. 1 is a front elevational view of a cabinet door showing my new design; and

FIG. 2 is a sectional view along line 2—2 of FIG. 1.
I claim:

The ornamental design for a cabinet door, substantially as shown and described.
